(57) **CLAIM**

The ornamental design for a pan with indented handles, as shown and described.

DESCRIPTION

FIG. 1 is a top side perspective view of a pan with indented handles;

FIG. 2 is a left side view of the pan with indented handles from FIG. 1;

FIG. 3 is a right side view of the pan with indented handles from FIG. 1;

FIG. 4 is a front side view of the pan with indented handles from FIG. 1;

FIG. 5 is a back side view of the pan with indented handles from FIG. 1;

FIG. 6 is a top side view of the pan with indented handles from FIGS. 1; and,

FIG. 7 is a bottom side view of the pan with indented handles from FIG. 1.

The broken lines showing are for the purpose of illustrating portions of the environmental structure and forms no part of the claimed design.
